United States Patent Office

Des. 187,966

Patented May 17, 1960

187,966

DISPLAY STAND FOR A PLATE AND SILVERWARE OR THE LIKE

Samuel Kirk Millspaugh, Baltimore, Md., assignor to Samuel Kirk & Son, Inc., Baltimore, Md., a corporation of Maryland

Application May 28, 1959, Serial No. 56,120

Term of patent 14 years

(Cl. D80—9)

FIG. 1

FIG. 3

Fig. 1 is a front perspective view of a display stand for a plate and silverware or the like embodying my new design.

Fig. 2 is a right side elevation thereof.

Fig. 3 is a front elevation thereof, the broken lines, showing a plate and silverware, being for illustrative purposes only.

I claim:

The ornamental design for a display stand for a plate and silverware or the like, as shown and described.
